8 Claims. (Cl. 260—453)

1

The present invention relates generally to higher alkyl 4-hydroxy-3-ethoxybenzoates and, more particularly, it relates to therapeutic products which are toxic to various pathogenic organisms and bacteria.

Various compounds have been found which are highly toxic toward the bacteria *Bacillus mycoides*. Furthermore, it has been found that the toxicity of such compounds toward this bacteria is indicative of their toxicity toward a great number of pathogenic organisms such as *Histoplasma capsulatum*, *Blastomyces dermatitidis* and *Coccidioides immitis*, and also toward other bacteria such as *Brucella abortus*, *Brucella suis*, *Staphylococcus aureus*, *Corynebacterium diphtheriae*, *Bacillus anthracis*, and alpha and beta streptococci.

An object of the present invention is the provision of new chemical compounds which are toxic to the bacteria *Bacillus mycoides* and the provision of novel processes for making these compounds. Another object is to provide more intermediate compounds from which the previously mentioned compounds may be easily made. A particular object of the invention is to provide a new compound which has greater toxicity toward this bacteria than any previously known compounds in this or related classes of compounds.

I have discovered that higher alkyl (eight to ten carbon atoms) 4-hydroxy-3-ethoxybenzoate is highly toxic to the bacteria *Bacillus mycoides* and that n-octyl 4-hydroxy-3-ethoxybenzoate shows a greater toxicity to the bacteria *Bacillus mycoides* than any compound in this or related classes of compounds known heretofore. In the latter connection, the other higher alkyl 4-hydroxy-3-ethoxybenzoates and previously known compounds in this and related series of compounds have been effective against the bacteria *Bacillus mycoides* only at concentrations ranging from 0.006 per cent to 0.15 per cent but I have found that n-octyl 4-hydroxy-3-ethoxybenzoate is effective against this bacteria at a concentration of less than 0.0006 per cent.

In general, the higher alkyl (eight to ten carbon atoms) 4-hydroxy-3-ethoxybenzoate is easily prepared from 4-hydroxy-3-ethoxybenzaldehyde by first preparing a higher alkyl 4-hydroxy-3-ethoxybenzimidate acid salt from 4-hydroxy-3-ethoxybenzaldehyde oxime. The acid salt is then hydrolyzed to produce the higher alkyl 4-hydroxy-3-ethoxybenzoate.

A process of this type is illustrated generally below by the following formulas, wherein R rep-

resents an alkyl chain containing eight to ten carbon atoms.

In general, the higher alkyl 4-hydroxy-3-ethoxybenzoates may be prepared in accordance with my novel process by first reacting 4-hydroxy-3-ethoxybenzaldehyde with a neutralized solution of a salt of hydroxylamine such as the hydrochloride, sulfate, or acid sulfate salts, which are readily available articles of commerce. This reaction results in 4-hydroxy-3-ethoxybenzaldehyde oxime which is converted to 4-hydroxy-3-ethoxybenzonitrile by dehydration of the oxime by a suitable dehydrating agent such as acetic anhydride. Other dehydrating agents may be used such as propionic anhydride, phosphorous pentoxide, and thionyl chloride.

When acetic anhydride is used to dehydrate the oxime, an intermediate product, 4-acetoxy-3-ethoxybenzonitrile, is formed. This intermediate product is then selectively hydrolyzed with an acid to provide the 4-hydroxy-3-ethoxybenzonitrile.

As before indicated, the benzonitrile is converted to an acid salt of higher alkyl 4-hydroxy-3-ethoxybenzimidate, this being accomplished by reacting the 4-hydroxy-3-ethoxybenzonitrile with a higher alkyl alcohol in the presence of an excess of an anhydrous acid while preventing nitration and demethylation, thereby permitting higher alkyl 4-hydroxy-3-ethoxybenzimidate to be isolated as the acid addition salt.

The anhydrous acid employed is preferably gaseous hydrochloric acid, though other acids, both organic and inorganic may be used, such as sulfuric and toluenesulfonic acids, without causing either nitration or demethylation. A

nitrating acid, such as nitric acid, or a demethylating acid, as for example hydroiodic, will result in decreased yields.

The higher alkyl 4-hydroxy-3-ethoxybenzimidate acid salt may be isolated or may be immediately and easily hydrolyzed, in a neutral or slightly acidic solution, to produce a higher alkyl 4-hydroxy-3-ethoxybenzoate, each of the benzoates being novel compounds of high purity which are very effective against the bacteria *Bacillus mycoides*.

EXAMPLE I

Preparation of n-octyl 4-hydroxy-3-ethoxybenzoate

In the preparation of n-octyl 4-hydroxy-3-ethoxybenzoate, 4 - hydroxy-3-ethoxybenzaldehyde oxime is first prepared by dissolving 498 grams of 4-hydroxy-3-ethoxybenzaldehyde in a hot (90° C.) solution comprising 144 grams of sodium hydroxide in 1800 cc. of water. To this mixture is added 251 grams of hydroxylamine hydrochloride, whereupon the combined mixture is stirred until cool. Upon addition of the hydroxylamine hydrochloride the oxime forms as an oil which solidifies upon cooling of the solution. The resulting solid is filtered, washed with water, and air dried to provide a solid melting of 102° C. Recrystallization of the solid from high boiling ether gives white crystals melting at 102° C.

The needles of 4-hydroxy-3-ethoxybenzaldehyde oxime are dehydrated by mixing 218 grams of the oxime with 640 grams of acetic anhydride and boiling the mixture under reflux for two hours. After refluxing, the solution is cooled and stirred into 2500 cc. of cold (15° C.) water thereby forming a white precipitate of 4-acetoxy-3-ethoxybenzonitrile. The precipitate is filtered, washed with water and dried so as to provide a solid which melts at 60° C.

The 4-acetoxy-3-ethoxybenzonitrile is then selectively hydrolyzed to 4-hydroxy-3-ethoxybenzonitrile by preparing a mixture of 156 grams of the former and 450 cc. of concentrated hydrochloric acid, the mixture being heated to 65° C. and until all of the solid has dissolved. The heated solution is cooled and 3000 cc. of cold (15° C.) water is added. The dilute solution becomes cloudy and is neutralized to pH 4.5 with dilute sodium hydroxide. An oil separates out of the neutralized solution and this oil solidifies upon standing. The entire mixture is then extracted with ether, the ether solution being dried and distilled to yield 4-hydroxy-3-ethoxybenzonitrile as a light colored solid melting at 66° C. Recrystallization from high boiling petroleum ether yields white needles melting at 66° C.

The solid benzonitrile is then converted to the acid salt of n-octyl 4-hydroxy-3-ethoxybenzimidate, this being accomplished by preparing a mixture of 50 grams of the benzonitrile, 41 grams of n-octyl alcohol, and 150 cc. of anhydrous ethyl ether, cooling the mixture in an ice bath, and bubbling gaseous hydrochloric acid into the mixture for one hour. After treatment with the gas, the mixture is capped with a calcium chloride tube and allowed to stand at room temperature for 24 hours.

Upon standing, a heavy precipitate separates out and is recovered by filtering, the precipitate being washed with ether and allowed to dry in air. The dried precipitate weighs .69 grams and comprises an almost white powder which melts at 154-155° C. The powder is purified by dissolving it in chloroform and precipitating it with anhy-

drous ether, the precipitate being white crystals which melt at 155° C.

The n-octyl 4-hydroxy-3-ethoxybenzimidate hydrochloride crystals resulting from the previous step may then be hydrolyzed to produce 4-hydroxy-3-ethoxybenzoate by mixing 46 grams of the salt with 250 cc. of water and boiling the mixture under reflux for two hours. This mixture is then extracted with ether and the ether washed with saturated sodium bicarbonate solution. The ether is then dried and distilled, the residue being distilled under reduced pressure to yield n-octyl 4-hydroxy-3-ethoxybenzoate as a colorless oil which boils at 182° C. at 1.5 mm. The index of refraction of the oil is n_D^{20} 1.5093. The oil solidifies on standing to a crystalline solid having a melting point of 32-33° C.

EXAMPLE II

Preparation of n-nonyl 4-hydroxy-3-ethoxybenzimidate hydrochloride

n-Nonyl 4-hydroxy-3-ethoxybenzimidate hydrochloride is prepared by following the procedure set forth in Example I for preparing n-octyl 4 - hydroxy-3-ethoxybenzimidate hydrochloride except that 45 grams of n-nonyl alcohol is employed.

EXAMPLE III

Preparation of n-nonyl 4-hydroxy-3-ethoxybenzoate

n-Nonyl-4-hydroxy-3-ethoxybenzoate is prepared by hydrolyzing the n-nonyl 4-hydroxy-3-ethoxybenzimidate hydrochloride prepared as in Example II. The salt is hydrolyzed in the same manner as the n-octyl 4-hydroxy-3-ethoxybenzimidate hydrochloride is hydrolyzed in Example I to provide n-nonyl-4-hydroxy-3-ethoxybenzoate.

EXAMPLE IV

Preparation of n-decyl 4-hydroxy-3-ethoxybenzimidate hydrochloride

n-Decyl 4-hydroxy-3-ethoxybenzimidate hydrochloride is prepared in the same manner as the n-octyl 4-hydroxy-3-ethoxybenzimidate hydrochloride is prepared in Example I except that 49 grams of n-decyl alcohol is used. This process yields n-decyl 4-hydroxy-3-ethoxybenzimidate hydrochloride as a white powder which melts at 155-156° C.

EXAMPLE V

Preparation of n-decyl 4-hydroxy-3-ethoxybenzoate

The n-decyl 4-hydroxy-3-ethoxybenzimidate hydrochloride of the previous example is selectively hydrolyzed in the same manner as the n-octyl 4-hydroxy-3-ethoxybenzimidate hydrochloride is hydrolyzed in Example I to produce n-decyl 4-hydroxy-3-ethoxybenzoate. In this process, a colorless oil boiling at 197° C. at 1.5 mm. is formed, the oil having an index of refraction of n_D^{20} 1.5110. The oil solidifies to a crystalline solid, as in Example I, which solid melts at 35-37° C.

Thus, the higher alkyl 4-hydroxy-3-ethoxybenzoates, which are toxic toward *Bacillus mycoides*, are easily prepared in accordance with my invention, this being readily done from the novel intermediate products, the acid salts of higher alkyl 4-hydroxy-3-ethoxybenzimidate.

The various features of the invention which are believed new are set forth in the following claims.

I claim:

1. A process for producing an alkyl ester of 4-hydroxy-3-ethoxybenzoic acid in which the alkyl constituent contains from eight to ten carbon atoms comprising the steps of reacting 4-hydroxy-3-ethoxybenzaldehyde with a salt of hydroxylamine, dehydrating the resulting 4-hydroxy-3-ethoxybenzaldehyde oxime to produce 4-hydroxy-3-ethoxybenzonitrile, reacting the benzonitrile with an alkyl alcohol containing from eight to ten carbon atoms in the presence of an anhydrous acid and under anhydrous conditions to produce the alkyl ester 4-hydroxy-3-ethoxybenzimidate acid salt, and hydrolyzing the acid salt to the 4-hydroxy-3-ethoxyalkylbenzoate.

2. The process for producing an alkyl ester of 4-hydroxy-3-ethoxybenzoic acid in which the alkyl constituent contains from eight to ten carbon atoms which comprises the steps of reacting 4-hydroxy-3-ethoxybenzonitrile with an alkyl alcohol containing from eight to ten carbon atoms in the presence of anhydrous acid and under anhydrous conditions to produce higher alkyl 4-hydroxy-3-ethoxybenzimidate acid salt, and hy-

5

drolyzing the acid salt to produce the 4-hydroxy-3-ethoxyalkylbenzoate.

3. The process for producing an acid salt of 4-hydroxy-3-ethoxybenzimidate which comprises the steps of reacting 4-hydroxy-3-ethoxybenzonitrile with an alkyl alcohol containing from eight to ten carbon atoms in the presence of an anhydrous acid and under anhydrous conditions while preventing nitration and demethylation.

4. The product n-octyl 4-hydroxy-3-ethoxybenzoate.

5. The product n-nonyl 4-hydroxy-3-ethoxybenzoate.

6. The product n-decyl 4-hydroxy-3-ethoxybenzoate.

7. A 4-hydroxy-3-ethoxyalkylbenzimidate acid salt in which the alkyl constituent contains from eight to ten carbon atoms.

8. An alkyl ester of 4-hydroxy-3-ethoxybenzoic acid, the alkyl constituent of said ester containing from eight to ten carbon atoms.
